E. R. MULCHAHEY,
 FIRING DOOR CONTROLLED FORCED DRAFT BLOWER FOR STEAM BOILER FURNACES,
 APPLICATION FILED MAR. 26, 1912.

1,090,820.

Patented Mar. 17, 1914.

UNITED STATES PATENT OFFICE.

EARL R. MULCHAHEY, OF PROVIDENCE, RHODE ISLAND, ASSIGNOR TO DRAFT REGULATOR COMPANY, OF PROVIDENCE, RHODE ISLAND, A CORPORATION OF MAINE.

FIRING-DOOR-CONTROLLED FORCED-DRAFT BLOWER FOR STEAM-BOILER FURNACES.

1,090,820.

Specification of Letters Patent. Patented Mar. 17, 1914.

Application filed March 26, 1912. Serial No. 686,340.

To all whom it may concern:

Be it known that I, EARL R. MULCHAHEY, a citizen of the United States, residing at Providence, in the county of Providence and 5 State of Rhode Island, have invented certain new and useful Improvements in Firing-Door-Controlled Forced-Draft Blowers for Steam-Boiler Furnaces, of which the following is a specification.

10 This invention relates to means connected to the firing door for automatically cutting off or controlling the volume of air intro-
duceable into the furnaces of steam boilers through the medium of steam blowers con-
15 nected with the furnaces, and it consists in the novel construction and arrangement of parts, as hereinafter set forth and claimed.

The object sought to be attained is pri-
20 marily to provide the pressure-blower of a steam-boiler furnace with means connected therewith and with the firing-door of the furnace, whereby the act of opening said door, as in charging the furnace with fuel, also acts to cut off altogether or to vary the
25 volume of steam and air issuing from the blower; the latter thereby remaining in a temporarily inoperative condition while the door is open. The act of closing the firing-
30 door causes the steam-blower to resume its normal working, *i. e.*, to again serve as a force-draft appliance. It may be added that the means employed for controlling the blower or auxiliary draft-device used is not dependent for its action upon the varying
35 pressure of the steam or upon its tempera-
ture, nor does the device control the move-
ments of the flue or supplemental damper; this latter is or may be fixed or manually adjusted with respect to the normal steam
40 required. The main flue or chimney damper and also said supplemental damper are not represented in the drawings, since they are not combined or associated with or dependent upon the present invention for control-
45 ling the degree of flue openings.

In the accompanying drawings, Figure 1 represents a partial front elevation of a steam-boiler furnace embodying my improvement, the parts being in the normal 50 working condition; Fig. 2 is a corresponding top plan view, portions, however, being omitted; Fig. 3 is a partial side view, the blower being in action; Fig. 4 is a front view, showing the firing-door open; Fig. 5 is 55 a corresponding top plan view, portions

being omitted; Fig. 6 is a partial side view, showing the firing-door open; and Fig. 7 is a detail plan view, in enlarged scale, showing portions of the firing-door connection in the closed condition.

The boiler front and setting are design-
60 nated by the letter A, while B and C indi-
cate the firing-door and ash-pit door, respec-
tively. A steam pressure-blower D of suit-
able construction extends into the furnace, 65 and is adapted to be normally actuated by steam from the boiler, or other source of supply, via steam pipe b and interposed steam valve a having a movable valve proper v. To the latter is secured a verti-
70 cally guided stem v¹ having a horizontally disposed lever l connected thereto. The outer or air-intake end of the blower D may consist of a fixed disk-like head having radiating circularly spaced alternating bars 75 and openings s and s¹, respectively; to the center of said head is movably fulcrumed a register-valve N of usual construction hav-
ing corresponding bars and openings s, s¹. Obviously, when the openings of the two 80 disks are uncovered or registering with one another, the air inlet passages of the blower are normally open, and are normally closed when the valve N is swung a short angular distance in the opposite direction to cover 85 the head openings.

The angular movements of the valve N are automatically controlled by suitably mounted members m, m¹, m², m³, the former, 90 m, being in direct connection with the steam-
valve lever l, and the latter, m³, jointed to the member N. Thus, it is apparent that the act of swinging the lever upward, as in open-
ing the steam-valve v, simultaneously uncovers or opens the air-inlet passages of the 95 blower for normal action. That is, the air of the forced draft appliance is discharged into the ash-pit under the grate; the ash-pit door obviously then being closed. See corre-
sponding condition of the ash-pit door C as 100 shown in Figs. 1, 2 and 3. Obviously, a con-
trary movement of the parts acts to close the steam and air-valves, thereby rendering them *nil*. See Figs. 4, 5, and 6.

Now, in order to automatically effect the 105 foregoing changes in controlling the artificial draft appliance by the movements of the firing-door, as in opening and closing it, a link e¹ is suitably jointed to the door B at e,
the opposite end of the link being jointed to 110

the free end of a crank-arm c , in turn pivoted at c^2 to a stand or bracket d , preferably fixed to the front side of the boiler setting. An independently movable arm d^1 is also 5 pivoted at c^2 ; to the outer end of arm d^1 is jointed the upper end of a rod d^2 , its lower end being joint-connected to said valve-lever l . To the arm c , and movable with it, is connected an arc-shaped member c^1 , adapted 10 to move angularly in an opening therefor formed in the arm d^1 . Thus, it will be seen that the act of opening the door B , as in firing, not only forcibly depresses the lever l and closes the steam-valve, thereby automatically 15 cutting off the supply of steam to the blower, but at the same time also shuts off the supply of outer air to the blower, thus rendering the latter inoperative or inert while the firing-door remains open. The act 20 of closing the firing-door will, on the contrary, automatically and simultaneously open the steam and air valves v and N , respectively, thereby causing the force-draft blower to resume its normal function.

25 The act of swinging open the firing-door to its normal extent, assuming the force-draft blower to be in normal operation, may involve a materially greater degree of angular movement than is necessary or desirable 30 to impart to the valve-operating lever l , therefore certain members of the device are constructed so as to work idly or with a degree of "lost motion." That is to say, the bent member c^1 of the arm c may move freely 35 with the latter while the door is being opened, say 60° , more or less, at which instant the continued opening movement of the door causes the member c^1 to engage the arm d^1 , connected by a link d^2 to the latter 40 and to the valve-lever, and force the latter downward, thereby temporarily closing the steam-valve v against the entrance of steam into the blower, the condition then being substantially as indicated in Fig. 4. The act 45 also closes the air-valve N at the same time. Owing to the novel construction of the elements connecting the forced-draft mechanism with the firing-door the latter may be opened temporarily some 50° to 60° without 50 materially affecting the normal action of the mechanical or artificial draft upon the fuel-combustion, assuming the flue-damper to have been previously set or adjusted. The idle or delayed action thus obtained may be 55 utilized by the fireman in cleaning the

grates, breaking up the fire-bed, &c. In closing the door, after firing, the major portion of the movement first takes up the said "lost motion" or "play" until the bent member c^1 , in its upward movement, engages the arm d^1 , 60 said contact being then continued until the door closure is completed, thereby automatically and positively opening the steam and air valves of the blower to resume the normal force-draft conditions, see Fig. 1.

65 My improved automatic force-draft appliance is simple in construction, capable of being readily and quickly installed, and also easily and positively actuated.

Obviously, changes or modifications in the 70 construction and arrangement of the parts may be made therein without departing from the spirit and scope of the invention.

75 By means of my improvement the normal forced draft air and steam are automatically prevented from entering the furnace while the firing door remains open, thus not only preventing draft action and its consequent cooling effect upon the fire and flue, but positively preventing "flare-back" or "back-draft" through the firing opening, the advantageous result being to materially reduce coal consumption, thus increasing the boiler's efficiency.

80 I claim:

85 In a steam boiler furnace, the combination of a normally open steam valve arranged to receive a supply of steam from the boiler, means connected with said valve and with the fire door of the furnace arranged to close 90 the valve upon opening said door, as in firing, a forced draft blower connected to and normally actuated by said valve, said blower having a controlled air inlet, means connected with an element of said valve-actuating device arranged to automatically cut off the supply of air to said blower simultaneously with the closing of the steam supply valve, and means arranged to open the respective air and steam passages to cause an 95 inflow of steam and air into the blower concurrently with the act of closing the fire door, substantially as described.

100 In testimony whereof I have affixed my signature in presence of two witnesses.

EARL R. MULCHAHEY.
